(57) **CLAIM**

The ornamental design for a tooth for use with a
microtrenching blade, as shown and described.

DESCRIPTION

FIG. 1 is an enlarged side view of an ornamental design of
a tooth for use with a microtrenching blade.

FIG. 2 is a reduced left front bottom view thereof.

FIG. 3 is a left back bottom view thereof.

FIG. 4 is a left front top view thereof.

FIG. 5 is a left back top view thereof.

FIG. 6 is a front view thereof.

FIG. 7 is a back view thereof.

FIG. 8 is a top view thereof; and,

FIG. 9 is a bottom view thereof.

The right and left sides of the tooth are mirror images of each
other. The broken lines in the drawings show a hole in the
tooth which is shown for purposes of illustrating portions of
the tooth for use with a microtrenching blade and form no
part of the claimed design. Lines of light weight which do
not connect to adjacent lines are provided to show contour
and are not to be construed as discrete surface features.
